Patented Nov. 4, 1924.

UNITED STATES PATENT OFFICE.

ALBERT RUSSO, OF PITTSTON, PENNSYLVANIA.

AIR HEATER.

Application filed October 11, 1922. Serial No. 593,767.

To all whom it may concern:

Be it known that I, ALBERT RUSSO, a citizen of the United States, residing at Pittston, in the county of Luzerne and State of Pennsylvania, have invented certain new and useful Improvements in Air Heaters, of which the following is a specification.

This invention has reference to improvements in that class of heating attachments used in connection with smoke pipes wherein provision is made for introducing cold air through the lower or base end of the said smoke pipe and in such manner that the said cold air, as it passes into the pipe, is heated and is then discharged from the said smoke pipe into another pipe or drum to be conveyed to an upper room or other place to be heated.

Heaters of the general character stated 20 have heretofore been provided, and so far as I know, with cold air receiving and heating chambers in the nature of a pipe section closed at the upper and lower end and located within the stove pipe and of sufficiently 25 less diameter than the stove pipe to provide for passing the products of combustion delivered into the smoke pipe, around the internal pipe, the latter and the stove pipe usually having connected aligned cold air 30 intakes at the bottom and similarly connected hot air outlets for delivering the heated air into the offtake to the room to be heated.

In the use of tubular internal pipes as cold air receivers, the smoke passage is usually so 35 restricted that the draft through the smoke pipe is more or less retarded thereby and in consequence, since the internal tubular cold air receivers take up the greatest internal space of the smoke pipe, heating the cold 40 air as it passes through the internal pipe is a slow process and a relatively expensive one.

My invention primarily has for its purpose 45 to provide an improved construction of cold air heating attachment for the ordinary smoke pipe for stoves, in which the internal or cold air chamber is so formed that there can be little or no retarding of the draft through the smoke pipe and the process of heating 50 the air passage or chamber within the smoke pipe is quickly and conveniently effected, and the said inner or cold air receiving chamber is peculiarly shaped, for being conveniently inserted and secured within the 55 smoke pipe, certain other details of construction and arrangement of parts being

also included in my invention, as will hereinafter be explained in detail, specifically pointed out in the appended claims, and illustrated in the accompanying drawings, in 60 which:

Figure 1 is a somewhat diagrammatical face view of my invention applied for use, parts being in section and illustrating the application of a two pipe arrangement. 65

Figure 2 is a transverse section, parts being in side elevation, of the two pipe sections shown in Figure 1.

Figure 3 is a detail perspective view of 70 one of the inner flat tubes constructed for being applied in a single pipe arrangement.

Figure 4 is a detail perspective view of an air port stop, hereinafter referred to.

Figures 5, 6 and 7 are detail horizontal sections on the lines 5-5, 6-6 and 7-7, 75 respectively, on Figure 1.

In the drawing, I have shown the smoke flue from the stove to the chimney as composed of two smoke pipe sections 1-1, tele- 80 scopically connected and with the lower or base section flared at the bottom edge for fitting over the smoke outlet flange on the top of the stove in the usual way.

While the two smoke pipe sections 1-1 85 are shown, it is obvious that my improvements may be combined with a single smoke pipe section or more than two smoke pipe sections, as the conditions, under which my improvements are to be used, may make desirable. 90

My improvements embody essentially a flat tube 2 of a width sufficient to cause its opposite edges 20, which are slightly convex to snugly fit against the opposite sides of the internal wall of the smoke pipe, to 95 which the said flat tube 2 is made fast in a manner presently explained.

In practice, the inner tube 2 is made of a stove pipe section of less diameter than the 100 diameter of the smoke pipe within which the tube is applied. For example, for an ordinary stove pipe 6 inches in diameter, I take another pipe section say 4½ inches in diameter and shape the said smaller diameter pipe section into flatwise shape, as is best 105 shown in Figure 6, from which it will be observed that when thus shaped the pipe section is broadened into a tube 6 inches wide with edge portions 20 for flatwise and closely fitting against the corresponding inner 110 sides of the smoke pipe.

It should be stated that by flattening the

4½ inch diameter pipe and bending the open ends thereof, onto each other and clamping the same together as at 23—23, the upper and lower ends of the tube 2 are tightly closed to provide, as it were, a chamber 3 into which the cold air is fed and through which said air passes, as it is being heated by the surrounding products of combustion as they pass through the smoke pipe to the chimney flue.

The advantage in reducing the smaller diameter pipe section to a flattened tube will be apparent when it is considered that were the 4½ inch diameter pipe used within the smoke pipe, the said smaller diameter pipe, by reason of taking up all of the space, (except an annular 1½ inch passage) in the smoke pipe, it would practically stop the draft of the stove and in consequence much more heat energy is needed for warming up a round internal pipe than is necessary when the said inner cold air chamber or passage is in the nature of a flat tube, say one inch across, since but a small part of the internal area of the smoke pipe is blocked thereby and a large hot air impacting surface is always present for receiving the full heating effect of the freely passing products of combustion as they travel from the stove outlet to the chimney flue ends.

It is to be understood that the internal tubes are made in sections and when two or more smoke pipe sections are used, a like number of internal flat tube sections are telescopically joined to form a cold air heating chamber which extends continuously from the inlet end to near the outlet in the upper smoke pipe section, it being also understood that where a plurality of the flat tubes are used and joined, as stated, the upper end of the upper tube and the lower end of the lower tube are flatwise joined to form the closure for the upper and lower ends of the said flat tube sections.

Near its lower end the internal tube is formed with cold air inlets 4 which align with apertures 12 near the lower end of the stove pipe; the upper end of the internal tube has outlets 13 which align with apertures 14 in the smoke pipe, the outlets in the flattened tube being in the opposite edges, which edges closely seat against the adjacent inner faces of the smoke pipe when the parts are assembled for use.

In the practical application of my improvements to a smoke pipe section to hold the several cold air inlet openings 4 and 12 at the bottom and the aligning outlets 13—14 at the top relatively air-tight, the several openings are of rectangular shape and the openings in the inner pipe or flat tube are somewhat narrower and of less length than their opposing registering openings in the smoke pipe, to provide internal flanges 15 that surround the openings in the opposite

edges of the internal tube. The flanges 15 are diagonally slit at their four corners to provide for bending the upper and the lower and the opposite side flange portions out through the openings 12 and 14 in the smoke pipe and for bending the said flange portions back over the adjacent edges of the openings in the smoke pipe to form clamps that rigidly secure the inner tube and the smoke pipe in proper operative condition.

When only one hot air outlet is used, as shown in Figure 1, the other outlet may be closed in any suitable manner and therefore in order to cut out the use of the cold air heating devices, when not needed, closure caps 17 may be used. They are designed to be snugly fitted into the cold air inlets or outlets through the smoke pipe, see Figure 4.

From the foregoing description, taken in connection with the accompanying drawings, the complete construction, the manner of assembling and the advantages of my invention, it is believed, will be readily apparent to those familiar with the construction of and use of improvements of the kind mentioned.

What I claim is:

1. In a cold air heater for stoves, the combination with the smoke pipe provided with an opening near the lower end and an opening near the upper end, of a relatively narrow flat tube closed at its upper and lower ends said tube having its opposite vertical edges adapted for snugly fitting against the opposite internal faces of the smoke pipe, the said edges being provided with an air inlet and an air outlet, the said air inlet and outlet in the tube aligning with the lower and upper openings respectively in the smoke pipe when the tube is applied within the smoke pipe and means for rigidly holding the flattened tube in operative connection with the smoke pipe.

2. In a stove pipe heater of the character described, the combination with a smoke pipe an opening near the lower end and an opening at the upper end; of a flat tube relatively narrow in cross section and of such a width that its opposite edges snugly fit the diametrically opposite bearing portions of the smoke pipe when fitted therein, the upper and lower ends of the flat tube being clamped together to form closures for the said tube ends, the opposite edges of the tube having an inlet and an outlet having straight sides and ends, the openings in the edges of the tube being of less length and width than the coincident openings in the smoke pipe, the corners of the openings in the tube being diagonally slitted whereby flanges are provided adapted for being drawn out through and clamped over the edges of the adjacent openings in the smoke pipe when the tube is in operative adjustment within the said smoke pipe.

3. As a new article, a cold air heater for stoves comprising a stove pipe section having an opening near its lower end and an opening near its upper end, a flat tube within the pipe section whose opposite edges abut the internal wall of the pipe section, the said tube being provided along one edge with an air inlet and an outlet in communication with the adjacent apertures in the

stove pipe section, the said flat tube having 10 its opposite ends closed and constituting a central vertical partition which extends lengthwise of the pipe section, the said tube having bendable portions adapted for clamping over the walls of the openings in the 15 stove pipe sections to rigidly sustain the tube within the pipe section.

ALBERT RUSSO.
